SHEET HOLDER

Andrew J. Unetic, Cleveland, Ohio, assignor to
 The Cleveland Pneumatic Tool Company,
 Cleveland, Ohio, a corporation of Ohio

Application February 2, 1942, Serial No. 429,349

10 Claims. (Cl. 85—5)

This invention relates to improvements in sheet holders, that is to say devices for clamping together through certain of the registering rivet holes two sheets to be joined together by riveting, these devices being used temporarily until a sufficient number of rivets have been set to hold the sheets against accidental movement relative to each other.

One of the objects of the invention is the provision of a device of this character which shall be simple and economical in construction, easily manipulated, and effective and certain in its operation.

Other objects and features of novelty will appear as I proceed with the description of that embodiment of the invention which, for the purposes of the present application, I have illustrated in the accompanying drawing, in which:

Fig. 1 is a vertical elevational view largely in vertical central section of a sheet holder embodying the invention shown in connection with a pair of pliers for manipulating the same.

Fig. 2 is a vertical sectional view of the holder only, the view being taken substantially on the line 2—2 of Fig. 1;

Fig. 3 is a vertical sectional view on a larger scale taken on the same plane as Fig. 1 showing the holder after the spring has been compressed and the plunger correspondingly depressed;

Fig. 4 is a sectional view on the same plane as Fig. 3 after the plunger has been projected through aligned rivet holes in a pair of sheets to be joined and pressure on the spring relaxed, permitting the device to clamp the sheets together.

Fig. 5 is a transverse sectional view on a larger scale, the view being taken substantially on the line 5—5 of Fig. 4; and

Fig. 6 is a transverse sectional view also on a larger scale taken substantially on the line 6—6 of Fig. 1.

In the drawing I have shown at 10 a metal cup provided with a rim 11, the lower edge of which is flat to provide a seat for the bifurcated jaw 12 of a pair of pliers 13 which may be used for manipulating the holder and compressing its spring 14. The latter surrounds the plunger 15 of the device and bears at one end against the head 16 of the plunger and at the other end against a metal washer 17 seated in the bottom of the cup. The lower, smaller diameter portion of the plunger projects through a hole in the bottom of the cup 10 and through washer 17 and is of such cross-sectional dimensions as to

fit closely the registering holes 18 in a pair of sheets 19 to be joined.

A slot 20 is cut through the plunger leaving a pair of parallel side walls 21 that are joined together at both ends. Washer 17 has a slot 22 therein of a width sufficient to take the plunger. It also has a short radial element or rib 23 which projects into the slot 20 of the plunger. This radial element is continued downwardly in the slot as shown in Fig. 4 at 24, and its exposed surface within the slot is inclined downwardly and outwardly to form what may be termed a diagonal cam.

In the larger diameter or body part of the plunger I drill an inclined hole upwardly in the plane of the slot 20 to receive one end of a resilient wire or finger 25 which takes a diagonal position in the slot approximately parallel to the diagonal cam 24, particularly when the plunger is extended as illustrated in Fig. 3. The lower end of this wire is bent to horizontal position forming a projection 26 which directly overlies the bottom of the slot 20, said projection adapted to be moved laterally with respect to the plunger 15. The bottom of the slot therefore forms an abutment 27 against which the projection 26 rests and by which it is reinforced and enabled to take the load which is imposed upon it in service.

30 In the use of the invention a holder is placed in a pair of pliers 13 in the manner illustrated in Fig. 1, that is the bifurcated jaw 12 of the pliers is caused to straddle cup 10 and engage the shoulder beneath rim 11, while the rounded face of the other jaw 28 is caused to engage the head 16 of the plunger. The operator then by drawing the handles of the pliers together compresses spring 14 and pushes the plunger down through the opening in the bottom of the cup as far as it will go, or to the position of Fig. 3. In this position the projection 26 is entirely retracted within the confines of the slot 20, so that the plunger may be lowered through a pair of registering rivet holes 18 until the bottom of the cup strikes the surface of the upper sheet 19. The operator then releases his grip upon the pliers, permitting the spring 14 to raise the plunger to the position of Fig. 4. The plunger in rising toward the latter position carries the finger 25 upward, causing it to wipe over the diagonal cam 24 and the radial element 23, thereby flexing the finger and camming its lower end forward so that the projection 26 protrudes beyond the surface of the plunger proper into position to engage the bottom sheet 19. When

the parts have reached this position, the operator removes the pliers and the sheets are pressed together by the spring acting to draw the abutment 27 upwardly and therefore to force the projection 26 upwardly, gripping the two sheets 18 between that projection and the bottom surface of the cup.

While I have described with considerable particularity one specific embodiment of the invention, it should be understood that variations from the disclosed structure may be resorted to. In particular, the projection which engages the sheets on the side opposite the cup may be differently mounted and the cam action which projects it may be differently constituted than in the disclosed embodiment. Also, in the embodiment shown the depending part 24 of the washer 17 may be omitted if desired, the cam action being effected by the radial element 23 only.

Having thus described my invention, I claim:

1. In a sheet holder, a cup the lower surface of which functions as an abutment for engagement with the outer surface of one of a pair of sheets to be joined, a slotted plunger extending downwardly through an opening in the bottom of the cup, a spring tending to raise said plunger, said plunger comprising a resilient finger fastened at its upper end to the body of the plunger and provided with a lateral projection at its lower end, said finger extending diagonally downward in the slotted plunger, and means at the bottom of the cup engaging the back of said finger for camming it forward as the plunger rises, whereby the lateral projection is caused to engage the outer surface of the other one of the said pair of sheets to be joined.

2. In a sheet holder, a cup the lower surface of which functions as an abutment for engagement with the outer surface of one of a pair of sheets to be joined, a slotted plunger extending downwardly through an opening in the bottom of the cup, a spring tending to raise said plunger, said plunger comprising a resilient finger fastened at its upper end to the body of the plunger and provided with a lateral projection at its lower end, said finger extending diagonally downward in the slotted plunger, means at the bottom of the cup engaging the back of said finger for camming it forward as the plunger rises, whereby the lateral projection is caused to engage the outer surface of the other one of the said pair of sheets to be joined, and an abutment on the plunger directly beneath said lateral projection to take the load imposed upon said projection.

3. In a sheet holder, a cup the lower surface of which functions as an abutment for engagement with the outer surface of one of a pair of sheets to be joined, a plunger extending downwardly through an opening in the bottom of the cup adapted to be projected through registering rivet holes in the said sheets, a spring tending to raise the plunger, said plunger comprising a resilient finger having at its lower end a lateral projection, and means carried at the bottom of the cup and cooperating with the said finger as it moves upwardly for camming said lateral projection forward into position to engage with the outer surface of the lower one of the said pair of sheets to be joined, said plunger also comprising an abutment directly beneath said lateral projection to take the load imposed upon said projection.

4. In a sheet holder, a cup the lower surface of which functions as an abutment for engage-

ment with the outer surface of one of a pair of sheets to be joined, a slotted plunger extending downwardly through an opening in the bottom of the cup, a spring tending to raise said plunger, 5 said plunger comprising a resilient finger fastened at its upper end to the body of the plunger and provided with a lateral projection at its lower end, said finger extending diagonally downward in the slotted plunger, and means at the bottom 10 of the cup comprising a diagonal cam for camming forward the finger as the plunger rises, whereby the lateral projection is caused to engage the outer surface of the other one of the said pair of sheets to be joined.

15 5. In a sheet holder, a cup the lower surface of which functions as an abutment for engagement with the outer surface of one of a pair of sheets to be joined, a plunger extending downwardly through an opening in the bottom of the

20 cup adapted to be projected through registering rivet holes in said sheets, a spring tending to raise the plunger, a lateral projection at the lower end of the plunger movable with respect thereto, and means carried at the bottom of the cup and

25 cooperating with the plunger as it moves upwardly for camming said lateral projection outward into position to engage with the outer surface of the lower one of said pair of sheets to be joined.

6. In a sheet holder, a cup the lower surface 30 of which functions as an abutment for engagement with the outer surface of one of a pair of sheets to be joined, a plunger extending downwardly, through an opening in the bottom of the cup adapted to be projected through registering

35 rivet holes in said sheets, a spring tending to raise the plunger, said plunger including a resilient finger having at its lower end a lateral projection movable relative to said plunger, and means carried at the bottom of the cup and cooperating with said finger as it moves upwardly for urging said lateral projection outward into position to engage with the outer surface of the lower one of said pair of sheets to be joined.

7. In a sheet holder, a cup the lower surface 40 of which functions as an abutment for engagement with the outer surface of one of a pair of sheets to be joined, a plunger extending downwardly through an opening in the bottom of the cup adapted to be projected through registering

45 rivet holes in said sheets, a spring tending to raise the plunger, a laterally movable projection at the lower end of the plunger, and a downwardly and outwardly inclined element projecting from said cup and cooperating with said plunger as it moves upwardly for urging said lateral projection outward into position to engage with the outer surface of the lower one of said pair of sheets to be joined.

8. In a sheet holder, a cup the lower surface 50 of which functions as an abutment for engagement with the outer surface of one of a pair of sheets to be joined, a plunger extending downwardly through an opening in the bottom of the cup adapted to be projected through registering

55 rivet holes in said sheets, a spring tending to raise the plunger, a laterally movable projection at the lower end of the plunger, a washer seated in the bottom of said cup and having an opening through which said plunger projects, and a downwardly and outwardly inclined surface formed on said washer and cooperating with said

60 plunger as it moves upwardly for camming said lateral projection outward into position to en-

gage with the outer surface of the lower one of the said pair of sheets to be joined.

9. In a sheet holder, a cup the lower surface of which functions as an abutment for engagement with the outer surface of one of a pair of sheets to be joined, a slotted plunger extending downwardly through an opening in the bottom of the cup, a spring tending to raise said plunger, said plunger including a resilient finger fastened at its upper end to the body of the plunger and provided with a lateral projection at its lower end, a washer seated in the bottom of said cup and having an opening through which said plunger projects, and a downwardly and outwardly inclined surface formed on said washer and cooperating with said finger as it moves upwardly for camming said lateral projection outward into position to engage with the outer surface of the lower one of said pair of sheets to be joined.

10. In a sheet holder, a cup the lower surface of which functions as an abutment for engagement with the outer surface of one of a pair of sheets to be joined, a slotted plunger extending downwardly through an opening in the bottom of the cup, a spring tending to raise said plunger, said plunger including a resilient finger fastened at its upper end to the body of the plunger and provided with a lateral projection at its lower end, a washer seated in the bottom of said cup and having an opening through which said plunger projects, a rib projecting from said washer into the slot of said plunger, and a downwardly and outwardly inclined surface formed on said rib and cooperating with said finger as it moves upwardly for camming said lateral projection outward into position to engage with the outer surface of the lower one of said pair of sheets to be joined.
